UNITED STATES PATENT OFFICE.

CHARLES T. LINDSAY, OF PITTSBURG, PENNSYLVANIA.

SHEAR-BAR FOR REINFORCED CONCRETE CONSTRUCTION.

No. 925,643.

Specification of Letters Patent.

Patented June 22, 1909.

Application filed September 29, 1908. Serial No. 455,356.

To all whom it may concern:

Be it known that I, CHARLES T. LINDSAY, a citizen of the United States, residing at Pittsburgh, in the county of Allegheny and 5 State of Pennsylvania, have invented certain new and useful Improvements in Shear-Bars for Reinforced Concrete Construction, of which the following is a specification, reference being had therein to the accompanying 10 drawings, forming part thereof.

My invention relates to reinforced - concrete and other cementitious constructions.

One object of my invention is to provide simple and effective means for rigidly binding 15 the reinforcing frame together and resisting the shearing strains through the concrete flooring or beam without in any way weakening the reinforcing frame.

Another object is to render the resisting 20 means self-locking against the pressure of the concrete, and adapted for use with different kinds and shapes of reinforcements.

Other objects are economy of manufacture, 25 simplicity of construction, facility of assembling the parts, and efficiency of operation.

Other objects and advantages of my invention will appear from the following description.

30 I shall now describe my invention with reference to the accompanying drawings and shall thereafter point out my invention in claims.

Figure 1 is a side elevation, partly in section, of a span of a reinforcing frame broken away at the middle and embodying my invention. Fig. 2 is a transverse section on an enlarged scale taken on the broken line $x-x$ of Fig. 1 looking toward the right. Fig. 3 35 is a sectional elevation of a portion of the shear-bar taken on the line $y-y$ of Fig. 2 looking toward the left, the concrete being removed and the girder being shown in dotted lines to more clearly illustrate the locking angle. Fig. 4 is a detail plan view of 40 a shear-bar twisted at the center, but in all other respects substantially the same as the bars shown in the previous figures.

In a span, such as is shown in Fig. 1, it 45 is a matter of common knowledge that the shearing stress follows a line running from the top near the columns or supports toward the bottom at the center. In addition, therefore, to the usual reinforcing girders 1 and 2 50 at the bottom of the concrete beam, other reinforcements are needed, at the top near the

ends and in the bottom at the middle. The girders 3 and 4 serve this purpose at the ends and extend an equal distance each side of the columns or supports. Extra reinforcements 60 may be laid in the bottom at the middle, supported by the cross-bonds 5 and 6, the former being shown in section. To hold this reinforcing frame rigidly and to resist the shearing strains, I connect the upper and 65 lower girders by a series of steel bars 7. These bars are shown as flat and provided with perforations or holes 8 to allow the bars to be passed on and form a connection between the corresponding upper and lower 70 reinforcements. It is evident that the perforations or holes 8 may be of any shape to adapt the bar for use with any shaped girder or reinforcement commonly used.

To be the most effective, the shear-bars 75 must extend between the reinforcements obliquely in a direction substantially perpendicular to the line of the shear, as shown in Fig. 1; the perforations or holes 8 are therefore punched straight through the bar 80 perpendicular to the flat faces as shown, so that the bars will be self-locking on the girders and will not be pushed out of place by the pressure of the concrete, since the holes 8, being slightly longer than the height 85 of the girder, fit about the girder at a locking angle. This angle is best illustrated in Fig. 3.

If it is desired, the shear-bars may, of course, be twisted at the center, as is shown 90 in Fig. 4, to form a mechanical bond.

It will be observed that with my invention I avoid punching holes in the girders, bending the bars, and other means commonly resorted to, which tend to weaken the construction. After my bars have been passed 95 on the end of the girders and pushed to their places, the pressure of the concrete securely locks the whole structure, and nowhere is the strength of the fiber of the steel impaired. 100

It is obvious that various modifications may be made in the construction shown and above particularly described within the principle and scope of my invention.

I claim:

1. In reinforced concrete construction, the combination with the main members of shear-bars connecting the main members and joined thereto at perforated portions fitting over the main members and having their longitudinal faces in planes transversely crossing the main members. 110

2. In reinforced concrete construction, the combination with the main members of shear-bars connecting the main members and joined thereto at flat perforated portions fitting over the main members at a locking angle and having their longitudinal faces in planes transversely crossing the main members.
3. In reinforced concrete construction, the combination with the main members of shear-bars adapted to connect the main members at an angle substantially perpendicular to the shearing force, the bars having flat

perforated portions with their flat faces in planes transversely crossing the main members and having elongated perforations the walls of which are perpendicular to the flat faces, and being arranged to fit over the main members at a locking angle.

In testimony whereof I have affixed my signature in presence of two witnesses.

CHARLES T. LINDSAY.
